United States Patent Office

Des. 198,246
Patented May 19, 1964

198,246

VTOL AIRCRAFT

Stanislaw F. Kwiatkowski, Columbus, Ohio, assignor to
North American Aviation, Inc.

Filed Nov. 14, 1962, Ser. No. 72,495

Term of patent 14 years

(Cl. D71—1)

FIG. 1 is a plan view of the VTOL aircraft showing my new design;

FIG. 2 is a side elevational view thereof;

FIG. 3 is a rear elevational view thereof;

FIG. 4 is a sectional view taken on line 4—4 of FIG. 1;

FIG. 5 is a sectional view taken on line 5—5 of FIG. 1. The dominant features of my design reside in the portions shown in full lines.

I claim:

The ornamental design for a VTOL aircraft, as shown and described.
